CAMPER TIE DOWN

Reed Rasmussen, 168 W. Gentile, Layton, Utah 84041,
and Carl M. Rasmussen, 197 East 1400 South, Bountiful,
Utah 84010

Filed Aug. 14, 1972, Ser. No. 280,709

Term of patent 14 years

Int. Cl. D8—08

U.S. Cl. D8—229

FIG. 4

FIG. 1

FIG. 2

FIG. 3

FIG. 1 is a perspective view of the camper tie down illustrated in the environment of a truck box for illustrative purposes only, the environment being shown in broken lines;

FIG. 2 is an exploded perspective view of the camper tie down with the generally U-shaped support member illustrated as oriented 180 degrees from the FIG. 1 position;

FIG. 3 is a side elevational view of the camper tie down (the right hand element of FIG. 2) depicting the dogleg offset construction of the latching flange portion relative to the mounting bracket portion; and

FIG. 4 is a front elevational view of the camper tie down of FIG. 3.

We claim:

The ornamental design for a camper tie down, as shown and described.
